J. R. BROWN, OF NEW HAVEN, CONNECTICUT.

Letters Patent No. 94,069, dated August 24, 1869.

IMPROVEMENT IN PIPE-COUPING.

The Schedule referred to in these Letters Patent and making part of the same.

To all whom it may concern:

Be it known that I, J. R. BROWN, of New Haven, in the county of New Haven, and State of Connecticut, have invented a new Improvement in Pump-Connection; and I do hereby declare the following, when taken in connection with the accompanying drawings and the letters of reference marked thereon, to be a full, clear, and exact description of the same, and which said drawings constitute part of this specification, and represent in—

Figure 1, a side view;

Figure 2, the same, turned one-fourth around; and in

Figure 3, a vertical central section of fig. 1.

This invention relates to an improvement in the means of coupling and adjusting pumps upon the pipe to which they are attached for the purpose of drawing water, especially to that class of pumps known as copper pumps; and

The invention consists in forming the pipe-connection upon a socket, which said socket forms the valve-seat, and the connection bent so as to carry the pipe-attachment to one side of the centre, the pump-cylinder formed with a ledge or flange, so that a yoke may be placed over the pump-flange, and, passing under the pipe-connection, is there fixed by a set-screw, which holds the pump upon the connection, so that it can, by the loosening of the screw, be adjusted to turn the cylinder into any desired position.

To enable others skilled in the art to make and use my invention, I will fully describe the same, as illustrated in the accompanying drawings.

A is the pump-cylinder, formed with a ledge or flange, *a*.

B, the socket, made to receive the lower end of the pump and also the valve C, the pump-cylinder sitting upon the rim of the valve to hold it in place, as seen in fig. 3.

To the socket the pipe-connection D is attached or formed thereon, the said connection being turned so as to form a double bend, as seen in figs. 1 and 3, thus starting from the centre of the socket B, is immediately carried to one side of the centre, so that a seat, E, may be formed upon the under side of the first bend. F is a yoke, fitted to set over the flange *a* of the pump, and pass under the seat E, as seen in figs. 1 and 2.

Through the said yoke a set-screw, I, passes, so as to bear upon the seat E, as seen in fig. 3, thus clamping the pump and pipe-connection securely together. If, at any time, it is desirable to change the position of the pump, or to change the spout into a different direction, loose the set-screw I, turn the cylinder to that position, and clamp as before.

Having fully described my invention,

What I claim as new and useful, and desire to secure by Letters Patent, is—

The combination of the socket B with the connection D, formed as described, with the flanged cylinder A, yoke F, and set-screw I, as and for the purpose specified.
